UNITED STATES PATENT OFFICE.

ROBERT CHARLES PESSELL, OF BATH, ENGLAND.

SIGNALING APPARATUS.

Application filed April 11, 1922. Serial No. 551,558.

To all whom it may concern:

Be it known that I, ROBERT CHARLES PESSELL, subject of the King of Great Britain, residing at 35 Westgate Street, Bath, England, have invented new and useful Improvements in Signaling Apparatus; and I do hereby declare the following to be a full, clear, and exact description of the invention, such as will enable others skilled in the art to which it appertains to make and use the same.

This invention relates to signaling apparatus and has for its object to provide an apparatus which will signal any predetermined message without the necessity of the operator having to know or to selectively reproduce the message being sent.

A means of signaling according to my invention comprises a number of contacts adapted to successively engage means adapted to operate or to be caused to be operated a signaling unit.

In order that my invention may be clearly understood and readily carried into effect I have appended hereto two sheets of drawings illustrating same wherein:—

Fig. 1 is a part sectional side elevation of the apparatus.

Fig. 2 is a vertical section on the line 2—2 of Fig. 1 the cover being removed.

Fig. 3 is an end elevation.

Fig. 4 is a sectional plan on the line 4—4 of Fig. 1.

Fig. 5 is a face view of one of the movable radial plates or keys.

Fig. 6 is cross section of the wheel on the line 6—6 of Fig. 1 drawn to a larger scale, and showing plate retained by annular coiled spring.

Referring to the drawings which illustrate a preferred construction of apparatus embodying the principle of my invention, three means of signaling are employed, two by visual signaling and one by sound. One means of visual signaling comprises a removable flag 1 carried by an arm 2 adapted to be moved in an arc of a circle after the manner of Morse signaling. This arm 2, which is preferably removable for packing purposes and may be curved or straight is pivoted at a point near its lower end by means of a pin 3.

Movement is imparted to the flag arm 2 by means of a vertically disposed arm 7 pivoted at its lowermost end by means of a pin

8 projecting from an end wall 9 of a box like casing 10. This arm 7 carries at its upper end a pin 11 which engages a slot 12 provided in the flag arm 2, so that any arcuate movement imparted to the pivoted arm 7 will be transmitted to the flag arm 2. To prevent the flag arm from falling below the conventional "ready" position illustrated by Fig. 2, an abutment 12^a of rubber or other suitable material is provided against which is adapted to engage the lowermost part of the flag arm 2.

The flag arm 2 and the arm 7 are mounted for movement across one face of a plate 13 secured to the end wall 9 of the casing 10. This plate 13 which may if desired carry the pivot pins 3 and 8 is formed with a transverse channel 14 the opposite side portions 15 of which are slotted at 16 to receive and serve as a guide for the arm 7.

Secured to the arm 7, or if desired formed integrally therewith is a transverse channel member or portion 17 having a substantially centrally disposed vertical slot 18 hereinafter referred to as the neutral slot. Disposed on the left (see Fig. 2) of this neutral slot is a V shaped or acute angled slot 19 and on the right of the neutral slot an obtuse angled slot 20. These three slots are adapted to be engaged by projections carried by a drum or wheel 21, for which purpose the slots merge into the opposite side portions 22 of the channel member 17 to allow the projections to engage therewith, the upper portion of the slots being slightly widened to provide an easy entry for the said projections.

The projections referred to constitute part of a number of plates 23 (see Fig. 5), the projections 24 being disposed at opposite ends of said plates. These plates are adapted to have an even and comparatively tight fit in a number of radial and transverse slots 25 disposed across the periphery of the drum 21. Provided around the centre of the peripheral surface of the drum 21 is a circumferential slot 26 about half the depth of the transverse slots 25, and sprung into this circumferential slot is a coiled spring band 27. This spring band 27 serves to maintain the plates 23 in selected positions in the transverse slots 25, and for this purpose the said plates are each provided along their edges disposed furthest from the centre of the drum 21 with three semi-circular slots,

a, *b*, and *c*, which slots are adapted to be tightly engaged by the spring band 27; so that each plate is capable of being set and maintained in any selected one of three lateral positions relatively of the drum 21.

When the plates 23 are in position in the drum 21 the projections 24 extend beyond the periphery of the said drum in such a manner that one of each pair of the projections will engage one of the three slots 18, 19, 20 in the channel member 17. Should a plate be arranged in a transverse slot 25 so that a projection 24 will engage the neutral slot 18, the projection will pass straight through said slot without affecting the position of the arm 7 so that the flag 1 will not be moved. Should however it be desired to signal a "dash" with the flag the plate 23 would be so positioned in a transverse slot 25 so that a projection 24 will engage the V shaped or acute angled slot 19, the downward pressure of the projection upon the edges of such slot imparting a comparatively wide sweeping movement to the said flag. Similarly should it be desired to signal a "dot" the plate 23 would be positioned for a projection to engage the obtuse angled slot 20.

The position of the plate shown in Fig. 6 and the plates in Fig. 4 are for sending "dots" from which it will be seen that the central semi-circular slot *b* is engaged by the coiled spring band 27; for sending a dash the slot *c* is engaged by the said spring band, and for neutral position the slot *a* is engaged. For clearness the slots are shown in Fig. 5 with the corresponding signal marked opposite each, the letter N indicating "neutral". If desired similar or equivalent marking may be effected in practice.

It will be seen from Fig. 4 that when a plate is set to signal a "dot" one projection 24 engaged the obtuse angled slot 20 and when sending a "dash" the other projection engages the V shaped slot, in both cases the non-engaging projection clearing the channel member 17. Similarly in the neutral position the same projection used for the "dot" passes through the slot 18 whilst the remaining projection clears the said channel member. If desired two colored rings may be marked around the peripheral surface of the drum 21 to indicate the positions opposite which the projections 24 should be set for "dash" and neutral positions.

It will be clear that by setting the plates in selected positions and rotating the drum 21, a message corresponding to the selected positions of the plates will be signalled by the flag 1. A starting position on the drum 21 may be provided by omitting a slot as at 28 (see Fig. 1) or by a colored mark.

The drum is supported for rotation by bearings 29, a spindle 30 carried by said drum and engaging said bearings being pro-

vided for this purpose. The bearings are detachably supported in the casing 10, by means of threaded pins 31 carried by said bearings engaging bayonet slots 32 provided on opposite sides of the casing 10; milled clamping nuts 31^a being screwed on to the outwardly projecting parts of said pins 31. The casing 10 is made in two parts the top part 10^a having one end wall omitted to enable it to fit over the end wall 9, the top of this part 10^a being shortened slightly to leave a clearance 33 through which the flag arm 2 projects.

Rotary motion may be imparted to the drum 21 by any suitable means, a preferred means being that illustrated by the drawings in which a relatively small wheel 34 is provided having a circumferential rubber band 35 engaging the inner face of a concentric upstanding rim 36 formed on the drum 21. A handle 38 is provided for rotating the wheel 34. Alternatively the rim 36 may take the form of a toothed annular and the wheel 34 be correspondingly provided with teeth, or a worm drive may equally well be provided.

A further means of visual signaling is by means of a lamp 39, suitably connected to a source of electric current such as a dry cell 40, the lamp being included in the circuit by means of a contact 41 on the arm 7 engaging a spring contact finger 42 connected to one terminal of the cell 40 and carried by an insulating block 43 secured to the end wall 9. Likewise a means of sound signaling such as a buzzer 44 may be similarly connected to the cell 40 so that the three means of signaling may be used simultaneously.

For switching the buzzer and lamp into circuit a pair of contacts 45, 46, are provided over which is adapted to be moved an arcuately movable contact finger 47, so that either the lamp or the buzzer may be selected, or by bridging the contacts both of them be used simultaneously.

As an alternative means of contact, the arm 7 may be provided with a spring finger adapted to engage a contact (the equivalent of the contact 42) the position of which may be adjusted so that the periodicities of the dots and dashes may be varied.

It will be apparent that the contact 41 of the arm 7 will remain in contact with the spring contact 42 longer during the sending of a "dash" than during the sending of a "dot" so that the lamp or buzzer will be illuminated or sounded for a time corresponding to the movement of the flag 1.

To maintain the drum 21 in correct alignment during its rotation a pin 48 is provided projecting from the plate 18 having a longitudinal head 49 engaging the slot 26.

If desired an ordinary signaling key may be connected to the lamp and buzzer so that

signaling may be effected without rotation of the wheel or drum 21.

I wish it to be understood that modifications may be effected in the apparatus hereinbefore described without departing from the spirit and scope of my invention.

What I claim is:—

1. Signaling apparatus comprising a signaling unit having grooves, and a plurality of movable members arranged to successively engage with and operate said signaling unit, said movable members having projections engageable with said grooves.

2. Signaling apparatus comprising a signaling unit, a movable member provided with slots, and a plurality of contact devices carried by said movable member and arranged to successively engage with and operate said signaling unit when the member is moved, said contact devices consisting of plates shiftably seated in said slots, and a single means associated with said movable member to hold all of said plates seated in the slots thereof.

3. Signaling apparatus comprising a signaling unit, a movable member provided with slots, and a plurality of contact devices carried by said movable member and arranged to successively engage with and operate said signaling unit when the member is moved, said contact devices consisting of plates shiftably seated in said slots, and means consisting of a coiled spring arranged in embracing relation to said movable mem-

ber and to all of said contact devices to hold the latter seated in the slots of the member.

4. Signaling apparatus comprising a signaling unit, a rotatable member, and a plurality of contact devices adapted to be secured to said member and upon rotation of the latter adapted to successively engage with and operate said signaling unit, said contact devices being adjustable with respect to said member whereby each device is capable of operating said signaling unit in different ways.

5. Signaling apparatus comprising a signaling unit including a movable arm formed with slots, and a plurality of movable contact devices adapted to successively engage with and move said arm, thereby to operate said signaling unit, said contact devices having projections engageable in the slots of said arm whereby the latter is moved in harmony with said devices.

6. Signaling apparatus comprising a signaling unit including a movable arm formed with a plurality of differently shaped slots, and a plurality of movable contact devices adapted to successively engage with and move said arm, thereby to operate said signaling unit, said contact devices having projections engageable in said slots whereby the arm is moved in harmony with said devices.

ROBERT CHARLES PESSELL.
